Primary Examiner — Samantha Q Lawrence*Assistant Examiner* — Holly M Rodriguez(74) *Attorney, Agent, or Firm* — LegalForce Rapc Worldwide(57) **CLAIM**

The ornamental design for a safety lancet, as shown and described.

DESCRIPTION

FIG. 1 is a front top-right side perspective view for a safety lancet, showing my new design;

FIG. 2 is a rear bottom-left side perspective view of FIG. 1 thereof;

FIG. 3 is a front elevational view of FIG. 1 thereof, the rear elevational view being a mirror image;

FIG. 4 is a left side elevational view of FIG. 1 thereof, the right-side elevational view being a mirror image;

FIG. 5 is a top plan view of FIG. 1 thereof; and,

FIG. 6 is a bottom plan view of FIG. 1 thereof.

The broken lines indicate unclaimed portions of the safety lancet and form no part of claimed design.

1 Claim, 6 Drawing Sheets(56)
